US00D910257S

(12) **United States Design Patent** (10) **Patent No.:** **US D910,257 S**
(45) **Date of Patent:** **** Feb. 9, 2021**

(54) **FLOOR CLEANING DEVICE**

(71) Applicant: **Alfred Kaercher SE & Co. KG**,
Winnenden (DE)

(72) Inventors: **Felix Schneider**, Stuttgart (DE);
Michael Meyer, Schwaikheim (DE)

(73) Assignee: **Alfred Kaercher SE & Co. KG**,
Winnenden (DE)

(**) Term: **15 Years**

(21) Appl. No.: **29/701,222**

(22) Filed: **Aug. 9, 2019**

(30) **Foreign Application Priority Data**

Feb. 18, 2019 (WO) 80438
